(57) **CLAIM**

The ornamental design for a tire, as shown and described.

DESCRIPTION

FIG. 1 is a perspective view of the tire of our design; FIG. 2 is a side elevation view of the tire of our design; FIG. 3 is a front elevation view of the tire of our design; FIG. 4 is an enlarged, partial view of the tire of FIG. 3, as indicated by the break lines; and,

FIG. 5 is a detailed view of the tire of our design, taken from the area identified in FIG. 3.

The dash-dot-dash lines define the peripheral boundaries of the claim. The broken line disclosure in the drawings depicts environmental subject matter forming no part of the claimed design. The tread pattern continues over the circumference of the tire.
